Specification for Design.

Patented Sept. 14, 1920.

Application filed February 6, 1920. Serial No. 356,743. Term of patent 7 years.

To all whom it may concern:

Be it known that I, HERMAN L. STRONGSON, a citizen of the United States, residing at the city of New York, borough of Brooklyn, in the county of Kings and State of New York, have invented a new, original, and ornamental Design for a Pouring-Spout for Cans, of which the following is a specification, reference being had to the accompanying drawing, forming part thereof.

Figure 1 shows a side elevation of a pouring spout.

Fig. 2 shows an end elevation thereof, which is a view taken at right angles to the Fig. 1.

Fig. 3 shows a bottom view of the pouring spout.

I claim:

The ornamental design for a pouring spout for cans, as shown.

HERMAN L. STRONGSON.
